ABSTRACT: A corrugated plate for use in the regenerative mass of a rotary regenerative heat exchanger has also alternating, approximately square-shaped, flat-topped protuberances between the corrugations so that the gas passage formed between it and an adjacent plate of the pack and defined laterally by the corrugations is alternately and regularly constricted and expanded.

ELEMENTS FOR REGENERATIVE HEAT EXCHANGERS

BACKGROUND OF THE INVENTION

The present invention concerns a metal heating element for regenerative heat exchangers, which is provided at specified spacings with parallel corrugations and protuberances that are arranged in between these corrugations. Such elements are bundled alternately with planar or shallowly undulated plates to form packs of metal heating elements, which packs are installed as the heat storage mass in the supporting structure of regenerative heat exchangers.

The parallel corrugations of these metal heating elements have the purpose of keeping the metal plates, which are lying alternately in the packs, at an equal distance from each other and of forming narrow channels parallel to the axial direction of the regenerator, through which the heat exchanging media periodically pass, alternating in counterflow, whilst the protuberances between the corrugations in the walls of the narrow gas passage ducts which are formed between the adjoining metal plates, are intended to create more favorable flow conditions for the heat exchange.

It is known in the art that for fulfillment of these requirements the metal plates must be packed as densely as possible, so that the gas passage ducts, which are formed between the alternately adjoining metal plates have the smallest possible hydraulic radii, which are normally chosen of a size ranging between 3 to 10 mm. In the range of gas velocities of 5-15 meters/second, which are usually used, such small hydraulic radii create a laminar flow, with a heat transfer which is substantially lower than that of a turbulent flow. The shaping of the gas passage ducts and consequently the design of the protuberances in the plates themselves has therefore a chief aim of influencing the flow in such a way that this results in heat transfer coefficients which will be approximately the same as those of turbulent flow.

For this purpose it has already been attempted to increase the extent of the heat transfer between the flowing gases and the metal plates by designing the walls of the narrow gas passage ducts irregularly and intermittently, whereby an increased vortex shedding within the flow is obtained.

Experience has shown, however, that stronger and irregular vortex sheddings of this type cannot increase the heat transfer proportionally to the increased loss in pressure during passage of the flow through a pack of such metal heating elements.

One example of what has, therefore, been normal practice to use in metal heating element packs for regenerative heat exchangers, are substantially planar or shallowly undulated plates alternately with stepped plates, bent parallel to the direction of flow, which were provided at specified spacings with either mammillated or steplike protuberances of small height, where the flow ducts between the plates had a hydraulic radius of approximately 3.5 mm.

SUMMARY OF THE INVENTION

The present invention has the object of improving the heat transfer in the narrow flow ducts between the metal heating elements, with the packing density remaining unchanged, by creation of periodically repeated delays and accelerations of the flow, which are connected with an increased turbulence.

According to the present invention this object is fulfilled in that the spacing metal heating element shape between the planar or shallowly undulated plates is provided at specified distances with deep corrugations, which run parallel to the direction of flow of media through the pack and delimit the small gas passage ducts between the metal plates, which form with a specified hydraulic radius small, rectangular flow cross sections for the gases, the broader delimitation walls of which have at intervals in the flow direction laminar protuberances, mainly of a square shape, which are alternately arranged and directed opposite to each other in such a way, that they constrict the flow cross sections at one position into a small gap and at another into a larger gap, the gaps differing by an equal

protuberance height, and this protuberance height amounting to approximately 50 percent of the distance of the plates from each other.

For further development of the invention the distance apart of the deep corrugations shall amount to 10-20 times the size of the hydraulic radius of the small flow passages between the metal plates, whilst the length along the direction of flow of the laminar protuberances between these corrugations shall amount to 10-15 times the size of this hydraulic radius.

DESCRIPTION OF A PARTICULAR EMBODIMENT

One part of an example of the invention is shown schematically in the drawing, which is a perspective, partly cutaway view.

It shows part of a metal element 1 with one wave of an approximately sinusoidal corrugation each of an amplitude $c/2 = 1.0$ to $1.2 r_h$, of a wave length of 1 to $6.3 r_h$ and parallel to each other at distances of $a = 10-20 r_h$, where r_h is the hydraulic radius of gas passage ducts which are formed by the corrugations. The plates 1 are made up into packs with shallowly undulated plates 2 or plane plates 2a alternately with the plates 1. The packs are placed in a regenerator chamber so that the corrugations are along the axial direction, and gas flow takes place in the directions of the arrows F1 and F2. The corrugations, parallel to the flow direction, space apart the plates 2 or 2a and the corrugated metal plates 1, so that the gas passage ducts are formed between them. The plates are placed alternately on each other. Only a portion of a whole pack is shown in the FIG.

Between the corrugations, therefore, there are generally rectangular section gas passage ducts. The major walls of these have, however, generally square-shaped flat ridges and furrows which are protuberances 3 pressed alternately from opposite sides into the spacing elements 1 at distances $b = 10-15 r_h$ and having in each case a transverse width of 0.8-1.0 b .

In the perspective illustration of the metal heating element 1 a cutaway portion of one of the metal plates 2 with shallow undulations has been shown on the top left-hand corner and also a next succeeding spacing element 1a. The undulations of these metal plates 2 which are alternately arranged between the metal plates 1 have an amplitude height of $0.4 r_h$ and an undulation length (wavelength) of approximately $5 r_h$.

Compared with these rather weakly undulated intermediate plates 2 the ridges of the laminar, approximately square protuberances 3 of the wider wall parts form within the gas flow ducts between the heating elements 1 and 2 alternately quite considerable cross-sectional constrictions and correspondingly big expansions, because their protuberance depth h amounts to approximately 0.3 to 0.7 r_h .

By means of a metal heating element pack, which is formed in this way with alternately assembled plane or undulated metal plates 2 or 2a and the metal heating elements 1 with deep spacing corrugations, running parallel to the flow direction, periodically repeated delays and accelerations of the flow are obtained within the flow ducts between the metal plates because of the considerable cross-sectional constrictions and the cross-sectional expansion being alternately provided thereto, which are due to the approximately b^2 and a protuberance depth h , said delays and accelerations increasing the turbulence to such an extent that compared to the previously conventional metal heating element pack, for example according to the German Utility Model 1,903,543, with parallel ducts and triangular flow cross sections, a considerable increase of the heat transfer coefficient is obtained in line with a simultaneous lowering of the pressure losses.

The proportional increase of the heat transfer FIGS. 70 amounts in the velocity range of the gas flow from 3-6 meters/second to approximately 20 percent whilst the pressure losses, compared to those of the previously used metal heating element packs, are about 40 percent lower, if flow velocities of up to 6 meters per second are concerned.

I claim:

1. In a regenerative heat exchanger element pack formed of alternately assembled metal plates and spacing plates, which spacing plates are provided at intervals with deep corrugations, running parallel to the flow direction of gases through the pack and delimiting gas passage ducts between the plates, the improvement comprising in the flow cross sections of these small gas passage ducts having a small hydraulic radius r_h and a generally rectangular cross section with major and minor walls, the major delimitation walls of which having at equal distances behind each other in the flow direction flat protuberances of a generally square shape and of a height h , which are alternately arranged and directed opposite to each other in such a way, that they alternately constrict the flow cross section of the gas passage ducts, whereby this protuberance height h amounts to $0.3-0.7 r_h$.

2. The improvement according to claim 1, being thereby characterized that one approximately sinusoidal corrugation each of an amplitude height of $c/2 = 1.0-1.2 r_h$ is provided at parallel distances of $a = 10-20 r_h$ in the spacing plates and parallel to flow direction.

3. The improvement according to claim 2 being thereby

characterized, that the approximately sinusoidal corrugation has an undulation length of 1 to $6.3 r_h$

5. The improvement according to claim 1 being thereby characterized that the approximately square protuberances are indented behind each other in flow direction at distances of $b = 10-15 r_h$, with an area size of approximately b^2 .

10 5. In a regenerative heat exchanger element pack, a metal spacing plate having a mean plane, parallel spaced-apart corrugations passing through that plane, and, between the corrugations, protuberances projecting out of the mean plane, adjacent protuberances in directions parallel to the corrugations projecting out of the said plane in opposite directions to an equal height, the said adjacent protuberances being flat surfaced and having a length equal to their width in a direction perpendicular to the direction of the corrugations.

15 6. A metal spacing plate according to claim 5 wherein the said adjacent protuberances are spaced apart, in a direction parallel to the corrugations, by a distance approximately equal to their length.
